UNITED STATES PATENT OFFICE

LEVI H. BERRY, OF JOPLIN, MISSOURI

GAS-HEATING MANIFOLD

Application filed March 17, 1928. Serial No. 262,469.

The present invention relates to internal combustion engines, and aims to provide a novel and improved manifold construction whereby the exhaust gases will heat the fuel mixture flowing to the engines, to provide for more perfect combustion, with a saving in fuel and other benefits.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawing, wherein—

Figure 1 is a view of the improved manifold construction, partly in side elevation and partly in section, and also showing a vapor generator assembled therewith.

Fig. 2 is a section on the line 2—2 of Fig. 1.

Fig. 3 is a side elevation of a modified construction, on a smaller scale.

The intake and exhaust manifolds of the internal combustion engine are indicated at 7 and 8, respectively, which have branches communicating with the intake and exhaust ports of the engine, as usual.

The intake manifold 7 has a cylindrical or tubular body portion 9 provided with the ends 10 and with the partitions 11 between the ends thereof, providing chambers 12 which have outlets 13 communicating with the intake ports of the engine, and said chambers have inlets 14 communicating with the arms of a bifurcated or forced trunk 15 of the manifold. The carbureter (not shown) is connected to the trunk 15 of the manifold for the flow of carbureted air through the manifold, as usual, the stream of carbureted air being divided and flowing through the two chambers 12.

Exhaust tubes or flues 16 are disposed longitudinally within the chambers 12, with their ends secured through the ends 10 and partitions 11 of the body portion 9, and the discharge end 17 of the exhaust manifold 8 abuts one end of the body portion 9, while the exhaust pipe 18 abuts the other end of

said portion 9, for the flow of the products of combustion through the flues 16. The flues 16 are heated by the exhaust gases, and the fuel mixture passing said flues will be heated, thereby thoroughly vaporizing the gasoline or other liquid fuel, to provide more perfect combustion, and to eliminate carbon and fuel wastage within the engine cylinders.

A longitudinal tie rod 19 extends through the body portion 9 of the intake manifold and connects the exhaust manifold 8 and pipe 18, to clamp the parts together, and gaskets are preferably provided between said parts to prevent leakage.

A coil 20 of a tube 21 embraces the body portion 9 between the partitions 11, so as to surround the central chamber 27 of said body portion 9, in order that the coil will be heated by the exhaust gases which flow in the chamber 27 between the two sets of flues 16. The tube 21 is supplied by suitable fuel from a tank 22, in order that the fuel will be converted into gas in the coil 20, and discharges from the tube 21 into a storage tank 23. A gas supply tube 24 extends from the tank or chamber 23 to the trunk 15 of the intake manifold, and has a suitable control valve 25, which may be opened, such as when starting the engine, for delivering gas into the engine manifold, so that the engine may be started quickly, especially in cold weather. The intake manifold is thus specially constructed to accommodate the coil 20 around the chamber 27 between the arms of the trunk 15.

Fig. 3 illustrates an intake manifold 7' wherein the tubes or flues 16' extend the full length of the body portion 9' of the manifold, to simplify the construction, the partitions 11 and chamber 27 being omitted, and the trunk or inlet portion 16' of the manifold being connected to the body portion 9' between the ends thereof.

The manifold construction provides for a saving in fuel, as well as eliminating carbon deposits in the engine and fouling of spark plugs.

Having thus described the invention, what is claimed as new is:—

1. The combination of intake and exhaust manifolds of an engine, the intake manifold

having a tubular body portion with partitions between its ends forming chambers between said partitions and ends, said chambers having outlets, and the intake manifold
5 having a bifurcated trunk communicating with said chambers, and flues in said chambers between said partitions and ends of said body portion, the exhaust manifold extending to one end of said body portion in communication with the corresponding flues, and
10 said body portion having a chamber between said partitions establishing communication between said flues, and gas supplying means having a coil surrounding the last-named chamber and connected to the intake manifold.
15

2. The combination of intake and exhaust manifolds for an engine, the intake manifold having two chambers with flues therein and
20 having an intermediate chamber establishing communication between said flues, the exhaust manifold communicating with the flues of one of the first-named chambers, and gas supplying means having a coil surrounding
25 said intermediate chamber and connected to the intake manifold.

In testimony whereof I hereunto affix my signature.

LEVI H. BERRY.
